UNITED STATES PATENT OFFICE.

ANDREW J. CHASE, OF BOSTON, MASSACHUSETTS, ASSIGNOR TO THE KANSAS CITY PACKING AND CHASE REFRIGERATING COMPANY, OF SAME PLACE.

DESIGN FOR A REFRIGERATOR-CASING.

SPECIFICATION forming part of Design No. 20,003, dated July 8, 1890.

Application filed May 27, 1890. Serial No. 353,383. Term of patent 14 years.

To all whom it may concern:

Be it known that I, ANDREW J. CHASE, a citizen of the United States, residing at Boston, in the county of Suffolk and State of Massachusetts, have produced a new and original Design for Refrigerator-Casings, of which the following is a specification.

The object of my design is to provide a novel, handsome, and attractive casing for roll-top refrigerators; and the leading features thereof reside in a base part having doors, a roll-top divided into a series of cover-sections, and a rectangular top surmounting the roll-top.

In the accompanying drawing the figure is a perspective view of a refrigerator-casing embodying my design.

In the drawing, the numeral 1 indicates the

rectangular base part of the casing, having at its front a pair of doors 2, a vertical panel 3 between the doors, and similar end panels 4. The roll-top 5 above the base part 1 is divided into a series of cover-sections 6, 7, and 8, and is surmounted by a rectangular top 9, having its front provided with a central mirror-panel 10 interposed between two sets 12 of small panels.

What I claim is—

The design for a roll-top-refrigerator casing, substantially as shown and described. 30

In testimony whereof I have affixed my signature in presence of two witnesses.

ANDREW J. CHASE.
